CATHODE RAY TUBES FOR TELEVISION AND LIKE PURPOSES

Eric Davies, Burnham-on-Crouch, England, assignor to
Marconi's Wireless Telegraph Company Limited, Lon-
don, England

Application December 21, 1954, Serial No. 476,667

Claims priority, application Great Britain
January 15, 1954

10 Claims. (Cl. 313—76)

This invention relates to cathode ray tubes for tele-
vision and like purposes and more specifically to such
tubes in which electro-magnetic scanning and focussing
coils are provided side by side around the neck of the
tube.

It is known in high quality television tubes, i. e., tubes 20
such as those used for television monitors, to supply to
the focussing coil fitted round the neck of the tube,
correcting wave components derived from the scanning
circuits of the tube in order to ensure the maintenance
of correct focussing during scanning. The provision of
focussing correction during deflection is particularly im-
portant, not only in high quality television tubes such as
are employed for monitoring purposes but in colour tele-
vision tubes generally, because, in colour television, de-
fective focussing is liable to cause very adverse effects
in the reproduced pictures and may destroy proper colour
registration altogether towards the edges of the screen.

In practice considerable difficulties are experienced
with tubes, especially high quality and colour television
tubes, having focussing and deflection coils next to one
another on the neck of the tube, since leakage fields
tend to cause undesired mutual interference between the
deflecting and focussing coils. In modern large screen
tubes with short necks such interference is apt to be very
objectionable, in part because the shortness of the neck
means that the coils must be close together, and in part
because of the extent of deflection involved in covering
a large screen.

Mutual interference between focussing and deflecting
coils cannot be satisfactorily eliminated by an ordinary
solid magnetic screen between the two coil systems, be-
cause such a screen induces losses which are reflected into
the circuits of the coils in question and such losses can-
not be tolerated in the high efficiency deflecting coil cir-
cuits which are necessary if economic scanning is to be
effected. The present invention seeks to reduce or sub-
stantially eliminate mutual interference between adjacent
focussing and deflecting coils without introducing any
but very small energy losses.

According to this invention there is provided a tele-
vision or like cathode ray tube of the kind having focus-
sing and deflection coils next to one another about the
neck thereof, wherein at least one magnetic screen is
mounted between said coils and said neck, the screen
being sub-divided and constructed so as to provide a
large number of magnetic paths, said paths together
presenting relatively low reluctance to magnetic lines of
force running substantially radially with respect to the
neck of the tube, and relatively high reluctance to mag-
netic lines of force running substantially parallel to the
axis of the tube.

In a preferred form of construction there is inter-
posed around the neck of the tube and between the focus-
sing and deflecting coils a magnetic screen constituted
by a fine wire of flattened toroidal form and made of ma-
terial having ferro-magnetic properties. The fine wire
may be of a suitable resistive alloy, but ordinary soft

2

iron is quite satisfactory. The wire may be wound on
an annular former which may be of insulating material
and has an inner diameter such as to pass the neck of
the tube and an outer diameter large enough to extend
radially beyond the coils. The thickness of the former
(if used) is made quite small so that the focussing and
deflecting coils can be quite close together.

In place of a former of insulating material a former
of conductive material, for example, copper, may be
used. Although this will introduce a certain amount
of eddy current losses are quite small due to the fact that
there is ferro-magnetic wire screening on both sides of
the copper and the disadvantage of these small losses is
more than offset by the improved screening provided
by the copper.

In some cases it is possible to use a self supporting
winding and dispense altogether with a former.

For a better understanding of the invention and to
show how the same may be carried into effect, reference
will now be made to the accompanying drawing, in
which:

Fig. 1 is a schematic representation showing a wound
screen, in position round the neck of a tube;

Fig. 2 is a schematic perspective view of the screen
removed from the tube; and

Figs. 3 and 4 show stages in the manufacture of a
modified form of screen.

Referring to the drawing, 1 is a neck of a television
cathode ray tube (shown broken away at both ends of the
neck) on which is mounted a focussing coil assembly 2
and a deflecting coil assembly 3. Between these two
coil assemblies and acting as a screen to prevent mutual
interference is a wound screen 4. The screen 4 consists
of an annulus 4a (Fig. 2) which may be either of in-
sulating material or of conductive material such as
copper, on which is wound a winding 4b of fine ferro-
magnetic and preferably resistive wire, for example,
enamel or oxide covered Nichrome wire of 38 S. W. G.
The two adjacent ends of the winding may be left open
or may be connected together. As will be seen in the
figures, the turns of the winding are substantially radial
with respect to the neck of the tube and, accordingly,
each side of it presents a very large number of radial
ferromagnetic paths for lines of force running radially
so that there is a relatively low reluctance magnetic path
for the fringing fields of both coils to prevent each from
coupling materially with the other. Suitable dimensions
for a screen 4 as fitted to an existing high quality monitor
tube are:

	Inches
Internal diameter	about 1½
External diameter	about 3¼
Thickness	about 1/16

These dimensions are, of course, in no way critical and
are chosen to suit the tube and coils in conjunction with
which the screen is to be used.

In a modification illustrated in Figs. 3 and 4, the an-
nulus 4a is dispensed with and the winding 4b is wound
back and forth in a zigzag so that it occupies a rectangular
area as shown in Fig. 3. The winding is then bent round
into an annulus as shown in Fig. 4. By using a suitable
impregnating material (not shown) the winding of Fig. 4
may be made self-supporting.

It is not necessary to constitute the screen by actual
windings of wire and any equivalent sub-divided ferro-
magnetic structure may be used, for example so-called
"wire cloth" or "woven wire," cut into an annulus and
having "wire threads" running approximately radially
may be used.

While I have described my invention in certain of its
preferred embodiments, I realize that modifications may

be made, and I desire that it be understood that no limitations upon my invention are intended other than may be imposed by the scope of the appended claims.

I claim:

1. A television or like cathode ray tube of the kind having focusing and deflection coils next to one another about the neck thereof, wherein at least one magnetic screen is mounted between said coils and said neck, the screen being sub-divided and constructed so as to provide a large number of magnetic paths, said paths together presenting relatively low reluctance to magnetic lines of force running substantially radially with respect to the neck of the tube, and relatively high reluctance to magnetic lines of force running substantially parallel to the axis of the tube.

2. A tube as claimed in claim 1, wherein said screen is constituted by a fine wire winding, the wire being made from a material having ferro-magnetic properties.

3. A tube as claimed in claim 2, wherein said winding is arranged upon an annular former, the latter having an inner diameter such as to pass said neck, and an outer diameter large enough to extend radially beyond the coils.

4. A tube as claimed in claim 3, wherein said former is of insulating material.

5. A tube as claimed in claim 3, wherein said former is of a conductive material.

6. A tube as claimed in claim 1, wherein said screen comprises a self-supporting winding.

7. A tube as claimed in claim 1, wherein said screen is constituted by a fine wire winding, the wire being made from an electrically resistive material having ferro-magnetic properties.

8. A tube as claimed in claim 1, wherein said screen is a sub-divided ferromagnetic structure of the kind hereinbefore set forth, and wherein said structure is of annular shape and is formed so as to provide a plurality of "wire threads" running approximately radially of said neck.

9. A tube as claimed in claim 1, wherein said screen comprises a winding, the wire in which is wound back and forth in a zigzag to form a rectangular area, said area being deformed in its plane to produce an annulus.

10. A tube as claimed in claim 1, wherein said screen comprises a winding, the wire in which is wound back and forth in a zigzag to form a rectangular area, said area being deformed in its plane to produce an annulus and wherein said annulus is impregnated to increase the rigidity thereof.
